UNITED STATES PATENT OFFICE.

JAMES J. FEARON, OF PHILADELPHIA, PENNSYLVANIA, ASSIGNOR TO THE QUAKER CITY DYE WORKS COMPANY, OF SAME PLACE.

YARN-DYEING MACHINE.

SPECIFICATION forming part of Letters Patent No. 424,190, dated March 25, 1890.

Application filed October 31, 1889. Serial No. 328,789. (No model.)

To all whom it may concern:

Be it known that I, JAMES J. FEARON, a citizen of the United States, and a resident of Philadelphia, Pennsylvania, have invented 5 certain Improvements in Yarn-Dyeing Machines, of which the following is a specification.

My invention consists of certain improvements in that class of yarn-dyeing machines 10 in which the skeins of yarn are strung upon bars carried by the arms of a reel rotating within an outer casing, in the lower portion of which the dyeing-liquid is contained, so that the skeins or hanks of yarn are carried 15 alternately through the dyeing-liquid and above the same.

One object of my invention is to improve the devices whereby warning is given to the attendant if the yarn-carrying bars are not 20 turned at the proper time, so as to change the position of the skeins or hanks, a further object being to insure the stoppage of the machine in the event of such failure. These 25 objects I attain in the manner hereinafter set forth, reference being had to the accompanying drawings, in which—

Figure 1 is a side view of a yarn-dyeing machine provided with my improvements. Fig. 2 is a perspective view of part of the 30 machine on a larger scale. Fig. 3 is a perspective view of another part of the machine, also on an enlarged scale; and Figs. 4 and 5 are respectively a longitudinal section, partly 35 in elevation, and a sectional plan view, partly in elevation, of part of the skein-guard for the reel constructed in accordance with my invention.

A represents the casing of the apparatus, to suitable bearings in which is adapted the 40 shaft B of the reel, in which the yarn-carrying bars are mounted, the reel having a series of radiating arms a, to bearings in which are adapted the journals of inner and outer bars b, free to turn in their bearings, one or both 45 of the journals of each of the outer bars having at the end a toothed disk d, upon which acts an arm or pawl f, hung to a shaft f', adapted to a bearing in the casing A of the machine, so that as each tooth of the disk

comes under the influence of the arm f said 50 disk will be turned thereby and the upper skein-carrying bar will be likewise turned, so as to impart the desired movement to the skeins thereon. The arm f acts upon the backs of the teeth of the disk d, which are 55 rounded or inclined, as shown in Fig. 2; hence if from any cause a skein-carrying bar is prevented from turning the back of the tooth of the disk d will raise the arm f, and advantage is taken of this movement to 60 sound an alarm, so that the failure of the machine to operate in the proper manner will be called to the attention of the dyer. For this purpose I provide the outer end of the rock-shaft f' with an arm g, which acts upon the 65 arm h of the valve h' of an air or steam whistle h², mounted upon a steam or air pipe i at one side of the casing A, the arm g being acted upon by a spring g', the tension of which is regulated by a set-screw g², so that the actuating-arm f may be caused to bear upon the toothed disk d with any desired degree of 70 pressure, a set-screw g³ serving as a stop to limit the backward movement of the arm g, and thus restrict the approach of the arm f 75 toward the toothed disk.

Alarm apparatus intended to call the attention of the dyer to the failure of the machine to operate properly has been heretofore used on machines of this class; but a gong has 80 been used as the alarm, and the operating devices have been so constructed that the spring for actuating the same was necessarily placed on the inside of the casing A, where, owing to the heat and the acid liquids of the dyeing- 85 bath to which it was subjected, it soon lost its temper and became inoperative.

By constructing the alarm mechanism in accordance with my invention, the spring, being on the outside of the casing, is entirely 90 free from these destructive influences, and hence remains permanently operative, while the whistle continues to sound the alarm until the machine receives attention, so that if there is any undue delay on the part of the 95 attendant in looking after an improperly-operating machine such delay is at once manifest to the superintendent of the dye-room,

whereas the tap of a gong is likely to pass unnoticed.

By the use of the rock-shaft f' , with its internal and external arms, a steam-tight bearing in the casing for the shaft is permissible, and the internal operating arm or pawl f swings in the same vertical plane as that in which the toothed disks d travel; hence there is no lateral or side thrust upon these disks, 10 such as would tend to bend or distort the same.

In many cases it is advisable to stop the machine when there is any failure on the part of the skein-turning device to properly operate, and for this purpose I provide the rock-shaft f' with an arm m , which is connected by a rod, cord, or chain m' to a bell-crank lever F , hung to a suitable bracket on the outside of the casing A , and connected to a retainer n for the arm G of a clutch-rod n' , so that the latter will hold a clutch-sleeve p in engagement with a clutch-sleeve on one of the driving-gears s of the machine, said gear meshing into a spur-wheel s' on a shaft H , 25 which has a worm t , meshing with a worm-wheel t' on the reel-shaft B .

When the skein-carrying bar b fails to turn and the arm f is raised by the toothed disk on said bar, the retainer n will be withdrawn 30 so as to permit the arm G to move under the influence of a spring v , and thus adjust the clutch p to a mid or inoperative position. The driving-shaft I is also connected to the shaft H by slow-speed gears $w w'$, which may 35 be thrown into gear by moving the clutch p still farther outward, the automatic device, however, being intended simply to permit the movement of the clutch out of engagement with the high-speed gearing, so as to effect 40 the stoppage of the machine. A belt-shifter may in some cases replace a clutch as a means of stopping the machine, and is hence regarded as its equivalent.

In order to keep the skeins within proper 45 lateral limits on the skein-carrying bars and prevent said skeins from coming into contact with the arms of the reel, I provide each of the arms a of the reel with an inwardly-projecting stud or bracket x , bolted to the arm 50 at its outer end and having at the inner end a tubular socket x' , into which are fitted the opposite ends of short segments of metallic tubing y , these segments extending from arm to arm and abutting against each other within

the sockets, so as to provide a metallic guard-ring extending completely around the reel some distance inside of the arms. By this means a permanent guard-rail, not affected by heat, moisture, or rough handling, is insured. 55

Having thus described my invention, I claim and desire to secure by Letters Patent—

1. The combination of the reel and its casing, the rotatable skein-bars carried by the 65 reel and each having a toothed disk, with an arm acting on the backs of the teeth of said disk and swinging in the same vertical plane as that in which the disks move, a shaft carrying said arm and projecting through the 70 casing, an arm on said shaft outside the casing, and a spring acting on said outer arm and serving to hold the inner arm in position for acting on the toothed disks, but permitting said arm to yield when a disk cannot 75 turn, substantially as specified.

2. The combination of the rotating reel and its rotatable skein-bars, a yielding turning device for said bars, a steam or air pipe having a whistle thereon, a controlling-valve 80 on said whistle, and a lever acted on by the bar-turning device and bearing against the valve-arm, whereby it moves the latter on the forward movement, but is retracted independently of it, so as to leave the valve 85 open, substantially as specified.

3. The combination of the rotating reel and its casing, rotatable skein-bars carried by said reel, a yielding turning device for said bars, a driving-clutch for the machine, 90 and means whereby said clutch is released on the yielding of the skein-bar-turning device, substantially as specified.

4. The combination of the rotating reel and its casing, the rotatable skein-bars carried by said reel, a yielding turning device for said bars, a clutch for throwing the machine into and out of operation, a clutch-operating arm, a retainer therefor, and means for connecting said retainer to the yielding skein-bar-turning device, substantially as specified. 95

In testimony whereof I have signed my name to this specification in the presence of two subscribing witnesses.

JAMES J. FEARON.
